UNITED STATES PATENT OFFICE.

FREDERICK DIETZ, OF NEW YORK, N. Y.

TUBULAR LANTERN.

SPECIFICATION forming part of Letters Patent No. 310,188, dated January 6, 1885.

Application filed November 26, 1883. (No model.)

To all whom it may concern:

Be it known that I, FREDERICK DIETZ, of the city, county, and State of New York, have invented certain new and useful Improvements in Tubular Lanterns, of which the following is a full, clear, and exact description, reference being had to the accompanying drawings, and to the letters of reference marked thereon.

10 My invention relates especially to devices employed with lanterns of that class known as "tubular," wherein side lifting-wires are used for raising the globe from the burner, and has for its object the provision of a holder 15 and lifter which will maintain the burner securely in place, whether the globe is in position or not, and which will provide ready means for tipping or tilting the globe and perforated plate when it is desired to remove the 20 globe.

To attain the desired end my invention consists, essentially, in a perforated plate or globe-holder united or affixed to a seat or ring encircling or partially encircling the burner-cone and pressing thereagainst, employed in connection with side lifting-wires, the ring being formed thereby or secured thereto, the perforated air-plate being pivoted to or resting upon said seat; and my invention also involves certain other novel and useful combinations or arrangements of parts and peculiarities of construction and operation, all of which will be hereinafter first fully described, and then pointed out in the claims.

35 In the drawings, Figure 1 is a view in elevation of a lantern wherein my improvements are employed. Fig. 2 is a plan view of the lower portion of the lantern, the upper part and the perforated plate being removed, 40 said figure showing the seat as formed by the lift-wire partially encircling the burner-cone. Fig. 3 is a like view showing the lifting-wires as attached to a flat ring encircling the burner-cone. Fig. 4 shows a wire ring as encircling 45 the cone, and Fig. 5 shows a perforated plate as pivoted to the ring-seat. Fig. 6 is a plan view of the tongue forming the pivot.

Like letters of reference, wherever they occur, indicate corresponding parts in all the 50 figures.

As heretofore constructed and arranged, in

lanterns of this class the lifting-wire has not hugged the burner-cone while passing there-around, and has not acted to retain the same in place upon the air-chamber. If the globe 55 in such a lantern became displaced, the cone and burner would fall, or be easily brushed from position, and when the globe and plate were tipped back there was nothing to hold said cone and burner in their proper place. 60 By my improved construction these serious difficulties and defects are overcome, and as the wire of the lifter, or the ring attached thereto, hugs the cone closely it cannot be shaken or accidentally knocked from its seat 65 when the pressure of the globe upon the perforated plate is removed.

A is the lifting-wire, made in one or more parts, as preferred. In Fig. 2 it is shown as made of a single piece and partially encircling 70 the burner-cone. In Fig. 3 it is shown as made in two parts, the lower extremities whereof are united to a sheet-metal ring, B, encircling the cone. This ring is provided with a perforation, b, through which the tongue 75 C passes after passing through a similar perforation in plate D. In Fig. 4 the lifting-wire is shown as encircling the cone.

Fig. 5 shows the perforated plate D as affixed to the encircling-ring by simply passing 80 the tongue C through said plate and fastening its lower extremity around the ring-seat.

I lay no claim herein to anything shown or described in Letters Patent No. 283,237, as my invention is an improvement thereon, in that 85 in my device the seat for the globe-supporting plate is interposed between said plate and the burner-cone, so as to bear against the latter and hold the same in place both when the globe is upright and when tilted.

Having now fully described my invention, what I claim as new therein, and desire to secure by Letters Patent, is—

1. In a lantern of the character herein described, the combination, with the side lifting-wires, the burner-cone, and globe-supporting plate, of a seat for said plate interposed between the same and the burner-cone and bearing against the latter both when the globe is upright and when tilted, whereby said seat is 95 caused at all times to hold the cone in place, substantially as and for the purpose set forth.

2. In a tubular lantern provided with globe-lifting side wires, a perforated plate or globe-holder, a burner-cone, and a seat for the globe-holder having the latter hinged thereto, the
5 said seat and its hinge bearing against the cone to throw the weight of the globe on the cone both when the globe is upright and when tilted, whereby the seat and globe will hold the cone in place at both such times, substantially as and for the purpose set forth.

In testimony that I claim the foregoing I have hereunto set my hand in the presence of two witnesses.

FREDERICK DIETZ.
